(57) **CLAIM**

The ornamental design for an automatic tablet packing machine as shown and described.

DESCRIPTION

FIG. 1 is a front-top perspective view of an automatic tablet packing machine showing our new design;

FIG. 2 is a rear-bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof;

FIG. 9 is a front-bottom perspective view thereof;

FIG. 10 is another front-top perspective view thereof; and,

FIG. 11 is an enlarged view of the part **11** delineated in FIG. 10.

The broken lines in the drawings illustrate portions of the automatic tablet packing machine which form no part of the claimed design.

1 Claim, 10 Drawing Sheets
